UNITED STATES PATENT OFFICE.

MYLES MAHONEY, OF MONTREAL, QUEBEC, CANADA.

LOCOMOTIVE BOILER.

Application filed January 15, 1925. Serial No. 2,581.

The principal object of the present invention is to provide a boiler which will in the main conform to present day standards but which will have a higher efficiency.

5 The salient features of the invention are:

(a) The construction and arrangement of parts obtaining a horizontal division of the fire tubes for the purpose of causing the deflection of a part of the fire gases through tubes in the evaporator above the fire box, and thereby increasing the evaporating surface and at the same time providing a safety element.

(b) Augmenting the circulatory action of 15 the water through the boiler.

More specifically stated the invention consists of a division of the fire tubes by the crown sheet cutting off the top group and connecting this top group to the top corner

20 of the fire-box at the back of the latter and to the smoke box at the front of the boiler barrel. These pipes of the top group are of particular configuration in that each is formed with an upwardly projecting bend,

25 thus causing the fire gases to impinge against the interior of these pipes in the vicinity of the bend, the effect being that this portion of each pipe is of much higher temperature than the remainder of the pipes in the group.

30 This structure, therefore, presents a safety zone because in the event of the level of the water in the evaporator sinking below what is considered a safe level the first point exposed is the bends in these pipes, and as these bends have a very high temperature they will rapidly burn out with the result that water or steam will be immediately projected into the portion of the fire-box contiguous to the door and an alarm be given to the engine crew.

35 If the leak is not noticed the upwardly extending bend inclining downwardly the portions of the pipes from the bend to the fire-box establishes a flow of steam and water from the boiler to fire-box thus putting out the fire before any damage results.

40 Another feature of the invention consists in the augmenting of the circulation of the water through the evaporator. The arch tubes are connected at their forward ends to the top of the front water leg of the fire-box and their rear ends are connected to the upper end of the rear water leg of the fire-box in the vicinity of the top rear corner of the fire-box. These arch tubes are made 45 of slightly increasing diameter from their lower to their upper ends. The upper rear

corner of the fire-box is formed with an upwardly extending chamber with which the top group of fire tubes communicate, and this chamber has the effect of reducing the 50 capacity of the evaporator at this point but not to such an extent that the capacity of the evaporator at this point is reduced below the capacity of the adjacent portion of the rear leg of the boiler. The effect is that a 55 siphoning action is produced because of the gradual increase of capacity of the arch tubes, the upper portion of the rear leg of the boiler, the portion of the evaporator above the chamber and the portion of the 60 evaporator immediately following. I have discovered that this gradual increasing of capacity of the water conductor has the effect of augmenting the circulation.

For full comprehension, however, of my 65 invention reference must be had to the accompanying drawings in which similar reference characters indicate the same parts and wherein:

Figure 1 is a diagrammatic longitudinal 70 sectional view of a locomotive boiler constructed according to my invention;

Figure 2 is a transverse vertical sectional view taken on line 2—2 Figure 1;

Figure 3 is a similar view taken on line 85 3—3 Figure 1;

Figure 4 is a sectional view taken on line 4—4 Figure 1 showing the front tube sheet;

Figure 5 is a similar view to Figure 1 of the fire-box end of the boiler; and

Figure 6 is a fragmentary diagrammatic longitudinal sectional view of the crown sheet and associated parts illustrating a different location of the upward bends in the safety tubes.

Figure 7 is a sectional view taken through one of the crown sheet tubes at the point *a* in Figure 1 and illustrating the bracket for supporting the tubes upon the crown sheet.

Locomotive boilers are constructed in 100 many different sizes but the same general construction and arrangement of the parts is adopted as standard in all sizes although minor changes such as in the number of tubes employed, combustion chamber, etc. 105 must of necessity be made to secure the desired efficiency for each size and I have therefore shown my invention embodied in a locomotive boiler of a size which will enable a clear and complete explanation of all 110 of the features of my invention.

It is to be distinctly understood however

that I do not confine the invention to this size as minor alterations may be made to suit requirements of different sizes without departing from the spirit of the invention.

Referring to the accompanying drawings the boiler barrel is indicated at 2, the firebox at 3, the back tube sheet at 4, the front tube sheet at 4^a, the fire tubes at 5, the superheater flues at 5^a into which the superheater units are inserted, the crown sheet at 6, the siphon arch tubes at 7, the arch brick supported thereon at 8, and the side and rear or back walls or sheets of the firebox at 9 and 10 respectively. The smoke box is indicated at 44.

The reference character 12 indicates the location of the crown sheet in locomotives of this particular size in standard locomotive practice of to-day while 13 indicates the normal working water level. It must be borne in mind that a water level must always be maintained to a sufficient depth to cover the crown sheet irrespective of any grade on which the locomotive may travel, otherwise that portion of the crown sheet which at any time in service becomes uncovered will be burned through causing serious loss of life and great damage.

Gauges are provided for indicating the water level but while evaporation is progressing, the water may be allowed to become so low as to uncover the crown sheet, due to carelessness of the enginemen, who through neglect of proper attention fail to keep the water at a safe level. Corroded or defective gauge cocks and water gauge glasses may indicate water levels which do not exist inside the boiler and other causes such as bad feed water, often render the in-

dications of water level to be safe when the level is actually at a dangerous depth. To overcome these dangerous uncertainties I provide a downward offset 14 in the crown sheet, preferably adjacent to the rear of firebox which makes it possible to extend one or more rows of fire tubes rearwardly over the crown sheet as indicated at 5¹, the rear ends of these extended crown sheet tubes having their ends mounted in the auxiliary tube sheet 14¹ constituted by the vertically disposed portion of the offset. In locomotive boilers of the smaller sizes it may be desirable to extend only one row of the tubes over the crown sheet as is illustrated, whereas in the larger sizes it might be desirable to extend one or more of the topmost rows. These extended tubes are sloped substantially in parallelism with the crown sheet towards the rear end of the firebox to locate their highest point preferably above the firebox. This construction and arrangement of parts is most advantageous. In the first place danger of the crown sheet burning is practically eliminated because the tubes must burn first, and the burning of the tubes would at once warn the engine men of the dangerous water level. Secondly, a greater heating surface is provided, the loss in firebox heating surface engendered by the lowering of the crown sheet being more than offset by the increased surface provided by the extended tubes. This is clearly shown from the following comparison which is based on "Coles' System" recognized as the standard basis of measurement for computing locomotive boiler evaporation and compares a standard locomotive boiler with the same boiler constructed according to my invention:

My improved boiler:

223-2"	O. D. tubes--19-11" bet.	= 2325 sq. ft. heating surface	× 8.35 = 19413 lbs.
30-53/8"	O. D. tubes--19-11" bet.	= 841 sq. ft. heating surface	× 10.13 = 8519 lbs.
11-31/8"	O. D. tubes--19-11" bet.	= 186 sq. ft. heating surface	× 11.25 = 2093 lbs.
11-31/4"	O. D. crown tubes--7-18" long =	72 sq. ft. heating surface	× 30.00 = 2160 lbs.
4-3"	O. D. tubes--arch tubes.....	41 sq. ft. heating surface	209 sq. ft. = firebox H. S. } × 55.00 = 13750 lbs.
		3674 sq. ft. = total	Total 45935 lbs.
			Steam per hr.

Existing boiler:

228-2"	O. D. tubes--19-11 bet.	= 2378 sq. ft. heating surface	× 8.35 = 19856 lbs.
32-53/8"	O. D. tubes--19-11 bet.	= 897 sq. ft. heating surface	× 10.23 = 9176 lbs.
4-3"	O. D. arch tubes 9-3 long.	26 sq. ft. heating surface	215 sq. ft. firebox H. S. } × 55.00 = 13255 lbs.

3516 sq. ft. = total Total 42287 lbs.

Steam per hr.

45935

My improved boiler total lbs. steam per hour.....	.....	.....	.....
Existing boiler total lbs. steam per hour.....	.....	.....	.....
Gain.....	.....	.....	.....

42287

3643

3448 lbs. steam per hour = 8.6% (approx.) additional evaporating capacity.

It will be seen that the gain in this particular instance is approximately 8.6% over the standard type. This additional evaporation per hour is equivalent to the addition of 23 tubes 2" O. D. to base boiler (spaced same as existing tubes). These additional tubes applied to base boilers would enlarge

base boiler diameter and cause considerable increase in weight. This increased evaporation capacity may vary according to the size of the boiler from 3% to 8%. Another advantage obtained with this arrangement is that the increased heating surface is applied to that portion of the boiler where it

will create the greatest circulation because the tubes are located in close proximity to the crown sheet causing a rapid evaporation of the water therebetween.

5 The offset 14 in the crown sheet may be located at any desired point but that location which I find preferable is adjacent the back of the firebox, where it forms an upwardly extending chamber in full open communication with the firebox. When so located the hot flame gases in the firebox are caused to impinge against the firebox back as indicated by the arrows in Figure 5 thereby increasing the value of the firebox heating 10 surface and causing a better circulation in the back water leg 15 which in the standard types is inclined to be sluggish.

Notwithstanding the fact that the lowering 20 of the crown sheet reduces the firebox cubical volume a gas flow is obtained in the present construction which results in a more complete combustion than would be obtained in a firebox having its crown sheet located at the standard level. This is due to the 25 fact that the extra exits provided by the crown sheet tubes create a more uniform distribution of the draft over the fuel bed than would be the case in standard locomotive fireboxes, the "pull" of the draft from 30 the crown tubes causing the gas flow to break away from its stream line formation over the brick arch. As a result the gases of greatest temperature and therefore the 35 lightest and of highest velocity rise to the highest part of the firebox behind the brick arch and enter the crown sheet tubes at approximately 700° Fahrenheit hotter than their temperature would be at the firebox tube sheet if they passed through the tubes 40 mounted in such sheet. The unconsumed particles of fuel and the heavier gases pass over the brick arch of the firebox into the combustion chamber 3^a which then has a 45 relatively larger volume than would be the case without the crown sheet tubes, owing to the fact that through the latter a large volume of gases is taken away which would otherwise have to pass through the combustion chamber. This separating action of 50 the gases which takes place behind the brick arch opening causes a better mixing of the products of combustion and loss due to the formation of carbon monoxide gases and other incomplete combustion is reduced to 55 a minimum. In addition the firebox back sheet 10 has a much more effective gas flow along its surface than is the case in locomotive fireboxes now in use and a vigorous circulation of the water behind the back 60 sheet and in the legs at the sides of the firebox, where the circulation is usually sluggish, takes place. Circulation tests in existing fireboxes show very little horizontal flow in the firebox legs owing to the fact that

the legs only have to provide a vertical circulation to replace the water evaporated over the crown sheet. By converting the firebox back sheet into a more active heating surface a greatly increased horizontal flow is obtained as larger amounts of water are 70 evaporated at the rear of the firebox and must be replaced. The crown sheet tubes will further increase the side sheet circulation because the "temperature center of gravity" is located further towards the rear 75 of the firebox, thus inducing water flow further along the firebox legs.

Another feature of my invention is the provision of means for causing a vigorous circulation of the comparatively cool water 80 at the bottom of the boiler barrel. This means consists of the arch tubes 7 which are gradually increased in diameter from their lower ends upwardly so that a siphon 85 action is obtained which draws the water from the bottom of the boiler barrel and discharges it into the water space at the upper rear part of the firebox. This flow induces a circulation up the back firebox water leg 15 and the rear portions of the 90 side legs 16 and 17. The effect of this upward chambered extension of the firebox and the gradual upward expansion of the arch tubes is that gradually increasing capacity is presented from the small ends of 95 the arch tubes where they are connected to the upper end of the forward water leg of the firebox and this increasing capacity continues through the arch tubes and through the upper portion of the back water leg and 100 through the portion of the evaporator restricted by the chamber, to the main body of the evaporator. A distinct siphoning action is produced by this increase of capacity 105 and the circulation is augmented to a considerable degree.

The large volume of water discharged from the siphon arch tubes is thrown over the top of the crown sheet and crown sheet tubes in its circuit of circulation towards the 110 front of the boiler so that the added heating surface of the crown sheet tubes are provided with a primary flow and volume of water to add to their effectiveness.

The velocity and volume of the water discharged through siphon tubes can be theoretically calculated as follows:

$$v = \sqrt{h2g}$$

v = velocity of water and steam discharged 120 (ft. per sec.).

h = head in feet = vertical height between upper and lower ends of tubes = (3½ feet).

$2g = 64.32$ 125
then $v = 15$ ft. per sec.

Area at upper end of tubes 5.375" I.
D. = 1575 sq. ft. Discharge at 15 ft. per

sec.=2.2625 cub. ft. per sec. For 5 siphon arch tubes the discharge is then 20362 cub. ft. per hr. each of steam and water (column gives greatest discharge of half water and 5 half steam).

The manner in which the various parts are secured together is not entered into in detail because the usual practice of locomotive boiler construction is followed. The 10 crown sheet however is preferably constructed in two parts 6 and 6¹ welded or riveted together as at 6², and the latter is preferably a half inch in thickness so that even if this plate becomes uncovered before the 15 tubes extending above the crown sheet burn through, the tubes will still burn through or collapse before the plate becomes heated enough to rupture. The plate 6¹ should be transversely arched concentrically to the 20 crown sheet 6. The connection of the arch tubes to the back firebox sheet may be effected by flanging the firebox back sheet and welding the ends of the tubes thereto.

Means is provided for locating the fire 25 tubes which extend over the crown sheet at a definite distance therefrom and for supporting the tubes and preventing their collapse in the event of burning. This means comprises brackets each consisting of two 30 parts 30 and 31 loosely connected by a pin 32, one part 30 being forked and embracing and reinforcing the tube it supports, and the other part 31 being secured to the crown sheet or back tube sheet. That portion of 35 each of the bracket parts 30 which embraces the tube is welded thereto and extends upwardly around the same above the horizontal diametrical plane of the tube so that burning of the tube, when it occurs, is localized at "a" and collapse of the tube prevented. The loose connection between the bracket parts permits relative expansion and contraction between the tubes and firebox. The upward bends B in the tubes also permit 40 expansion and contraction of the latter. Figure 6 shows a different location in the upward bends in the tubes, the bends being located nearer the rear ends of the tubes so that the burning points B¹ are nearer the 45 flame gases which enter the tubes. This ensures a rapid burning of the tubes when they become uncovered. The tubes are reinforced adjacent their highest points by reinforcing members 40 which embrace the 50 tubes in a similar manner to the bracket members 30 shown in Figure 1 and prevent the collapse of the tubes in the event of burning. As alternative means of supporting the tubes, nuts adapted to form seats for 55 tubes may be mounted upon the crown sheet radial stays, or fixed struts may be mounted upon the crown sheet.

To facilitate the removal of sediment from the crown sheet washout plugs 50 are pro-

vided as usual in the outside wrapper sheet 65 in line with the crown sheet top surface so that such surface may be conveniently washed off.

It will be seen from the foregoing description that a safety boiler is provided in so far 70 as the collapse of the crown sheet due to burning occasioned by low water, is concerned, because it is impossible to burn the crown sheet without burning the safety tubes first. 75

Accepted practice in fire tube lengths is a ratio of sectional area of tube outside diameter to its length in inches of between 70 and 73 to 1. The ratio of the safety tubes 80 extending over the crown sheet in the illustrated embodiment is 40 to 1. It will seem therefore that this ratio is well within the accepted practice.

It is obvious that the nearer the upward 85 bend in the crown sheet tubes is located to the rear end of such tubes the more rapid the burning or collapse of the same when uncovered, and it is to be distinctly understood that the location of the bend may be varied to meet requirements without departing 90 from the scope of the present invention.

What I claim is as follows:

1. In a locomotive boiler the combination 95 of a boiler barrel; a smoke-box; a fire-box the crown sheet whereof has an upwardly extending chamber at the top rear corner thereof and in open communication with the fire-box; fire tubes communicating with the fire-box and extending through the barrel to the smoke-box, and safety fire tubes communicating with the chamber and extending through the barrel above the fire-box for the purpose of directing a portion of the burning gases therethrough from the top of the rear end of the fire-box to the smoke-box, 100 each of such safety fire tubes having an upwardly extending bend adapted to direct steam and water into the upwardly extending chamber in the event of a break in the bend. 105

2. A locomotive boiler such as claimed in 110 claim 1 the upward bends of the safety tubes whereof are located in the vicinity of the tube sheet.

3. A locomotive boiler; a fire-box; a 115 smoke-box; fire tubes extending rearwardly over the fire-box and communicating at one end with the fire-box and at their opposite ends with the smoke-box each of such tubes having a bend in an upward direction and 120 extending from the bend downwardly towards the ends of the boiler, and means for supporting the tubes upon the fire-box and for reinforcing them adjacent their bends.

4. In a locomotive boiler the combination 125 with a fire-box and the front and rear walls thereof, of an upwardly extending chamber in the crown sheet at the rear corner thereof

and in full open communication with the fire-box, fire tubes leading forwardly from the front wall of the fire-box, a row of fire tubes leading from the front wall of the chamber and extending forwardly over the crown sheet and a series of upwardly expanded arch tubes leading from the lower portion of the front wall of the fire-box to a point in the rear wall of the fire-box close to the chamber. ¹⁰

In testimony whereof I have signed my name.

MYLES MAHONEY.
